CLOTHES HANGER

John M. Wilson, San Diego, Calif.

Application May 21, 1956, Serial No. 586,013

4 Claims. (Cl. 223—88)

The present invention relates generally to garment hangers and more particularly to a clothes hanger having a somewhat resilient body with novel clothes retaining means.

The primary object of this invention is to provide a clothes hanger which has novel wings which engage the waist bands of skirts, ladies' slacks, men's trousers or the like and suspends and supports such garments in a wrinkle-free manner, with the weight of the garment utilized as an agency for tightening the hold of the wings on the garment.

Another object of this invention is to provide a clothes hanger in which certain body portions are resiliently expandable for better gripping action, this feature being additive and auxiliary to that mentioned in the preceding object.

Another object of this invention is to provide a clothes hanger of the aforementioned character having shoulder portions by means of which a coat or the like may be supported in wrinkle-free manner simultaneously with one of the before mentioned nether outer garments.

Another object of this invention is to provide a clothes hanger in which said shoulder portions have a secondary function as finger holds for manipulation of the wings.

Another object of this invention is to provide a clothes hanger which, in the smaller sizes thereof serves as a support for trousers and slacks in inverted position.

Another object of this invention is to provide a clothes hanger which is adapted for fabrication from many different materials, so that the choice of material can be according to the dictates of availability and price considerations, the exact sizes and proportions being matters easily determined to suit particular conditions and needs.

Another object of this invention is to provide a hanger which is practicable and inexpensive to manufacture.

Finally, it is an object to provide a clothes hanger of the aforementioned character which is simple, safe and convenient to use and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawings which form a material part of this disclosure, and in which:

Figure 1 is an elevational view of my invention and showing the normal or undeflected position of the wings.

Figure 2 is an elevational view of the instant hanger in expanded position and a skirt, only fragmentarily shown, suspended therefrom, the position of maximum upward deflection of the wings being indicated by dash line.

Figure 3 is an elevational view of a modified form of the hanger, the wings being joined together by a resilient coil portion.

Figure 4 is a perspective view of still another modified form of the hanger which, when made in a reduced size,

2

is ideal for engagement with the individual cuffs of trousers or the like.

Similar characters of reference indicate similar or identical elements and portions throughout the specification and throughout the views of the drawings.

Referring now specifically to Figures 1 and 2 of the drawings, the clothes hanger is shown as comprising a stem 10 having a hook 12 at the upper end, and a body, generally indicated by the numeral 14, comprising a single length of slightly flexible and resilient wire, rod or the like. It will be understood that although the preferred embodiment utilizes plastic rods for both the stem 10 and the body 14, the cross-sectional shape is by no means critical and said stem 10 and body 14 may be made of elements having a cross-sectional shape other than round, such as square, and oval rods, or even flat spring steel, while still implementing the instant invention.

The body 14 is provided with a single downwardly extending pocket 16 into which the lower end of the stem 10 is inserted and permanently affixed therein by slight deformation in a press, thermal union or any other suitable means, the upwardly extending sides 18 of the pocket providing for increased area of contact and great rigidity in the attachment.

It will be understood that the pocket 16 is located centrally of the body 14, and the wings 20, 20 comprise upwardly divergent portions 22 and outwardly disposed portions both incorporating a series of convolutions 24. The convolutions 24 are disposed, in a general sense, in a vertical plane and include garment-engaging elements in the form of substantially straight and substantially vertical portions or surfaces 25.

Stops 26, extending slightly outwardly from the top of the outermost convolution 24, serve to limit the insertion of an opposed pair of the convolutions 24 into the waist band 28 of a skirt 30 or similar article of clothing, it being understood that the skirt 30, illustrated only in Figure 2, is merely representative of a great number of articles which may be suspended in this manner.

Opposed shoulder bars 34, unitary with the stops 26, converge upwardly toward the stem 10, the upper end portion of each bar 34 being bent to constitute a finger pull 38 in spaced relation with the stem 10.

If reference now be had specifically to Figure 2, the action of the hanger becomes immediately apparent. If the body 14 is deflected into the position as indicated by dash line or the position of maximum upward deflection, the convolutions 24 are moved both upwardly and inwardly, i. e., toward the stem 10, obviously decreasing the distance between opposing pairs of garment-engaging surfaces 25. Now, if the waist band 28 of a skirt 30 or similar article is engaged with a pair of said surfaces 25 when the body 14 is in the deflected position, and the finger pulls 38 then released, the body 10 immediately springs toward the undeflected position as shown in Figure 1, increasing the distance between the said pair of surfaces 25 and biasing the same outwardly against two opposed points of the waist band 28, gripping the waist band 28 and allowing the garment to depend therefrom in a natural manner.

Obviously, since the waist band 28 is securely held in the aforesaid manner, there can be no sagging of the band 28, and therefore no subsequent permanent distortion is experienced as is quite common in other types of hangers.

A linear element such as a small chain 40 or the like terminably engaging the finger pulls 38, or looped thereabout, and extending therebetween is provided to prevent inadvertent overloading and consequent overdeflection downwardly. It will be also noted that a jacket or the like, not shown in the drawings, may be hung in the conventional manner upon the shoulder bars 34, since substantially all bending is localized in the portions 22 and

convolutions 24 as clearly indicated by the dash line representation in Figure 2 and the chain 40 prevents over-deflection.

Referring now to Figure 3 of the drawings, there is shown a modified form of the invention. A hanger of this general type can be fabricated from heavy gauge, relatively inflexible wire. The stem 44 has a hook 46 on its upper end and the body, generally indicated by the numeral 48, comprises a single length of wire or the like. The body 48 is provided with a single helical coil 50, secured to the lower end of the stem 44, and legs 52, unitary with the coil, extend divergently upwardly from the lower side of the coil. The legs 52 are provided with convolutions 54, garment-engaging elements 55 and stops 56, analogous to the convolutions 24, element 25 and stops 26 of the foregoing embodiment. Shoulder bars 58, unitary with the stops 56, extend convergently upwardly toward the stem 44 and these shoulder bars have finger pulls 60 constituting loop ends with returned portions 62 welded or otherwise fixedly attached, as indicated at 64, adjacent to the ends of the stops 56.

It now becomes evident that a substantial portion of the deflection is provided for by the coil 50, while the reinforcement of the structure at 64 due to said welding substantially eliminates bending at the points 64, while a chain 66 extending between the finger pulls 60 and attached thereto prevents over deflection downwardly when a coat or the like is suspended upon the bars 62. The waistband portion of a garment, not shown in Figure 3, is held securely between opposing pairs of convolutions 54 due to the outward biasing of the convolutions 54 in exactly the same manner as in the first described embodiment.

If reference now be had to Figure 4, a second modification of the instant hanger is shown as comprising a stem 70 having an upper hook portion 72, the lower end of the stem 70 being fixedly attached to a transverse spanner bar 74. The bar 74 is provided with depending legs 76, said legs having portions 78 bent to lie horizontally. As in the previously disclosed forms, the body 80 is fabricated from a single length of resilient wire and is bent to provide spaced parallel wing elements 84 diverging slightly upwardly from the portions 78 to which they are rigidly secured as by welding. The ends of the legs 84 are bent as at 86 and extend upwardly to constitute garment-engaging elements 88, analogous to a single pair of the convolutions 24, 54 previously disclosed herein. Stops 90 extending normally outwardly from the upper end of the portions 88, are analogous to the previously disclosed stop portions 26, 56.

The portions 94 terminate in loops constituting finger pulls 96. This embodiment of the instant hanger is adapted, when made in small sizes, for supporting slacks and trousers in inverted position, engagement therewith being accomplished merely by biasing the finger pulls 96 toward each other, and then inserting the wing elements individually into the cuff of the garments with the portions 88 in registration with the normal creases of said cuffs. Release of the pulls 96 allows the legs 84 to return toward the undeflected position, biasing the portions 88 outwardly and securely holding the garments in inverted position. It will be obvious that the distance between the garment-engaging portions 88 must be slightly greater than the span of the cuffs wherewith the device is to be used.

The operation of this invention will be clearly comprehended from a consideration of the foregoing description of the mechanical details thereof, taken in connection with the drawing and the above recited objects. It

will be obvious that all said objects are amply achieved by this invention.

Further description would appear to be unnecessary.

It is understood that minor variation from the form of the invention disclosed herein may be made without departure from the spirit and scope of the invention, and that the specification and drawing are to be considered as merely illustrative rather than limiting.

I claim:

- 10 1. A garment hanger comprising: a supporting stem having a hook at the upper end; a pair of opposed wings having garment-engaging elements and having their adjacent ends secured to the lower end of said stem; said wings being slightly flexible and resilient and extending divergently upwardly from said lower end; whereby the weight of clothes supported on said wings tends to pull said wings downwardly with consequent increase of spacing between the corresponding elements on the opposing wings; and means on said wings for temporarily decreasing the divergence to facilitate attachment and detachment of garments and comprising shoulder bars terminally secured to said wings and extending therefrom toward said stem to points adjacent to each other, said finger pulls on the ends of said bars adjacent said stem.
- 15 2. A garment hanger according to claim 1 and including a linear element secured to and extending between the adjacent ends of said bars.
- 20 3. A clothes hanger comprising: a supporting stem having a hook at the upper end thereof; a body including a pair of opposed wings of slightly resilient material secured in fixed relation at their adjacent ends to the lower end of said stem and diverging upwardly therefrom; said wings having garment-engaging elements therein; shoulder bars in fixed relation with the outer extremities of said wings and extending convergently upwardly toward said stem to points adjacent to each other; finger pulls on the ends of said bars adjacent said stem for manipulation by one hand, whereby said shoulder bars may be pulled toward said stem, thereby deflecting said wings upwardly to facilitate manipulation of the hanger into the garment-supporting position and to release a garment from the hanger.
- 25 4. A clothes hanger comprising: a supporting stem having a hook at the upper end thereof; a body including a pair of opposed wings of slightly resilient material secured in fixed relation at their adjacent ends to the lower end of said stem and diverging upwardly therefrom; said wings having garment-engaging elements therein; shoulder bars in fixed relation with the outer extremities of said wings and extending convergently upwardly toward said stem to points adjacent to said stem, finger pulls on the ends of said bars adjacent said stem, whereby said shoulder bars may be pulled toward said stem, thereby deflecting said wings upwardly to facilitate manipulation of the hanger into the garment-supporting position and to release a garment from the hanger; and means to limit the downward deflection of said wings; said means comprising a flexible linear element terminally secured to said finger pulls and extending therebetween.
